Clinton D Palmer,

By Miller & Chindobe
Atlys

Inventor.

UNITED STATES PATENT OFFICE.

CLINTON D. PALMER, OF CHICAGO, ILLINOIS, ASSIGNOR TO SEARS, ROEBUCK AND COMPANY, OF CHICAGO, ILLINOIS, A CORPORATION OF NEW YORK.

COMMERCIAL INSTRUMENT.

1,275,297.

Specification of Letters Patent. Patented Aug. 13, 1918.

Application filed October 31, 1914. Serial No. 869,500.

To all whom it may concern:

Be it known that I, CLINTON D. PALMER, a citizen of the United States, residing at Chicago, in the county of Cook and State of Illinois, have invented certain new and useful Improvements in Commercial Instruments, of which the following is a specification.

This invention relates to vouchers, due 10 bills, checks, drafts, money orders, and other commercial instruments of various kinds. The invention has been shown in the drawings as applied to a credit voucher and will thus be referred to herein for the sake of 15 brevity, without, however, intending any limitation of the invention.

In various lines of business, as for example, in the sale of merchandise by mail, it is necessary to issue large numbers of credit 20 vouchers, many of which are for amounts under one dollar; and it is obviously important to reduce to a minimum the labor involved in the issue and auditing of such vouchers. Heretofore, it has been necessary 25 to write the amount upon both the instrument and the stub, or if the amount appeared upon the instrument in the form of a printed marginal number, it was still necessary to write a corresponding amount upon 30 the stub. When the voucher was returned for redemption, it was necessary to compare it with the stub, in order to ascertain that the voucher had not been fraudulently altered. Such writing, handling and auditing 35 constituted a serious burden of expense which was particularly objectionable in the case of vouchers for small amounts.

One of the objects of the invention is to prevent alteration of the value of the instrument 40 or the stub from which the instrument is detached.

Another object is to produce an instrument and stub which shall be self-auditing, no comparison of the redeemed instrument 45 with its stub being necessary.

Another object is to obviate the necessity of writing the amount upon the instrument or the stub.

The invention contemplates the provision 50 of rows of bisected rectangular spaces and a series of pairs of consecutive numerals in said spaces, the numerals of each pair being identical and being positioned in opposite halves of the bisected spaces, and the numerals of the series being arranged with the

larger denominations toward the stub end of the sheet. The voucher proper is detachable from the stub along a line which bisects the space containing the numeral of the amount for which the voucher is issued, so that the 60 said amount is represented by the highest numeral on the detached check and also by the lowest numeral on the stub.

In the drawings, Figure 1 represents a sheet constituting a credit voucher and its 65 stub embodying the features of my invention. Fig. 2 represents the voucher and stub as being dated and detached from each other along the proper line.

In the preferred embodiment of the invention which I have shown in the drawings, there is provided a series of vertical lines 7 and a crossing series of horizontal lines 6 forming rectangular spaces. These spaces are bisected by diagonally extending lines 7. 70 A series of pairs of numerals, preferably in consecutive order, occupy the spaces, the two numerals of each pair being identical and being located in the opposite halves of a bisected space. The series of numerals is 75 arranged with the smaller denominations at the voucher side of the series and the larger ones at the stub side. In the present instance there are ten horizontal rows of spaces and ten vertical rows, the first vertical row 80 at the right-hand edge of the series containing pairs of numerals from 1 to 10 running downwardly, the second row from 11 to 20, etc.

The voucher may have printed thereon 90 the words "Issued for the largest printed marginal amount" or equivalent expression, while the stub may have thereon the words "Issued for the lowest printed marginal amount" or the like.

Assuming that the voucher is drawn for seventy-seven cents, the voucher would be detached from the stub along a vertical line running down from the top along the left of the row of "70's", thence along the bisecting diagonal line 7 dividing the space containing the numerals 77 into two halves, and thence down the vertical line at the right of the row of "70's". This line of division is indicated in Fig. 2. As will be seen, 105 the highest numeral on the detached voucher is 77, so that it will be impossible to "raise" the voucher by trimming off any portion thereof since that would lower the indicated value of the voucher. The lowest numeral 110

on the stub is also 77, so that the clerk issuing the voucher cannot possibly defraud his employer by trimming off a portion of the stub because that would indicate that 5 the voucher had been issued for a higher amount than it really was.

It will be understood that my invention is not limited to the particular arrangement of lines and numerals shown in the drawings, and, in fact, it would be possible to dispense with the lines altogether and employ only the row of duplicate numerals. The lines, however, assist in indicating the place to tear in detaching the voucher.

15 In tearing the voucher from its stub, a straight edge of a type well known may be employed which has an off-set or diagonal edge corresponding to the angle and length of a section of the line 7 bisecting a single 20 space.

If desired, the voucher and the stub may be dated by means of a rubber stamp.

It will be seen that the instrument herein disclosed cannot be fraudulently altered, and 25 its use necessitates no writing. Inasmuch as the voucher and the stub must necessarily show the same amount, the voucher is self-auditing.

The invention is useful in making any 30 kind of remittance; and is applicable to any purpose where a stub record of the same value as the original is required.

It will be understood that the size and shape of the number-bearing spaces, and 35 the angle of bisection may be varied to suit the conditions under which the instrument is to be used.

I claim as my invention:

1. A written instrument of the character 40 described comprising a body portion and a stub portion, and having on one face thereof crossing lines forming a plurality of columns of rectangular spaces, and lines

bisecting said spaces, each space having a pair of duplicate numerals, the pairs of numerals being consecutively arranged in sets transversely of the sheet, the value of the denominations of each set being less than the denomination of the next adjoining set nearer the stub, the numerals of each pair 50 being arranged on opposite sides of the bisecting line of their space, whereby the sheet may be divided along any one of the crossing lines running transversely thereof and along any of said bisecting lines to separate a rectangular space into halves, the numerals occupying the separated portions of such space being the highest of the series of numbers remaining on the body and the lowest of the series of numbers remaining 60 on the stub.

2. A commercial instrument of the character described comprising a sheet having one face thereof provided with a series of columns of consecutive numbers arranged in pairs of duplicate numbers, the duplicate numbers of each pair being arranged on the sheet diagonally with respect to each other, the pairs of numerals being consecutively arranged in sets, with the columns extending transversely of the sheet with the value of the denominations of each set being less than the denomination of the next adjoining set nearer the stub, whereby the sheet may be cut in two with a portion of the cut passing between the diagonally disposed numbers of any pair to provide a main body and a stub each containing one of the duplicate numbers of the pair between which the cut is made.

In testimony whereof, I hereunto set my hand in the presence of two witnesses.

CLINTON D. PALMER.

In the presence of—

IRA A. STONE,

C. M. GARMON.
